DESIGN FOR A SPRAY NOZZLE

Harper Richards, Chicago, Ill., assignor to Rilling Company, Minneapolis, Minn., a corporation of Minnesota

Application November 29, 1945, Serial No. 124,175

Term of patent 7 years

(Cl. D91—3)

To all whom it may concern:

Be it known that I, Harper Richards, a citizen of the United States, residing at Chicago, in the county of Cook and State of Illinois, have invented a new, original, and ornamental Design for a Spray Nozzle, of which the following is a specification, reference being had to the accompanying drawing, forming a part thereof.

In the drawing—

Figure 1 is a side elevational view of a spray nozzle showing my new design.

Figure 2 is a top view of the spray nozzle shown in Figure 1; and

Figure 3 is a bottom view of the spray nozzle shown in Figure 1.

I claim:

The ornamental design for a spray nozzle, substantially as shown.

HARPER RICHARDS.
